United States Patent

Des. 236,325
Patented Aug. 19, 1975

236,325

PACKAGE FOR CATHETERS

David Carleton Miller, Camillus, N.Y., assignor to
Ethicon, Inc., Somerville, N.J.

Filed Aug. 8, 1973, Ser. No. 386,814

Term of patent 14 years

Int. Cl. D9—106; D24—04
U.S. Cl. D9—187

FIG. 1 is a perspective view of a package for catheters of the present invention;

FIG. 2 is a top plan view of the package for catheters;

FIG. 3 is a side elevation of the package for catheters;

FIG. 4 is a cross sectional view taken along line 4—4 of FIG. 2, and

FIG. 5 is a cross sectional view of the package taken along line 5—5.

I claim:

The ornamental design for a package for catheters, as shown and described.
